UNITED STATES PATENT OFFICE.

JAMES H. CROW, OF DULANEY, ASSIGNOR OF ONE-FOURTH TO J. W. FLETCHER, OF PRINCETON, KENTUCKY.

TOBACCO-PRIZE.

SPECIFICATION forming part of Letters Patent No. 450,576, dated April 14, 1891.

Application filed January 17, 1890. Serial No. 337,266. (Model.)

To all whom it may concern:

Be it known that I, JAMES H. CROW, a citizen of the United States, residing at Dulaney, in the county of Caldwell and State of Kentucky, have invented a new and useful Machine for Prizing Tobacco, of which the following is a specification.

My invention relates to certain new and useful improvements in tobacco-prizing machines; and it has for its principal object the production of a machine of this class in which the pressing mechanism, after having completed its work on the tobacco in one hogshead or other vessel, can be swung clear of that hogshead and into position over another placed in its path of travel, thereby permitting an empty hogshead to be filled in a position to be operated on by the pressure mechanism while the contents of a filled hogshead are being pressed.

Another object of my invention is the production of a machine of this kind which will be simple in its construction, and which can also be easily taken apart and put together when it is desired to move it from place to place.

The invention will first be described in connection with the accompanying drawing, which is a perspective view of my machine, and then pointed out in the claims.

Referring to the drawing, A represents the platform of the machine, constructed of two stringers 1, united in the middle by a cross-beam 2 and at each end by a cross-beam 3. On the ends of the stringers are formed cylindrical projections 4, for a purpose which will hereinafter appear.

B represents a square post, preferably of iron, whose lower end is socketed in the middle portion of cross-beam 2, and for the purpose of supporting this post in a vertical position there is a metal plate 6 slipped over it, from which extend brace-rods 7, whose lower ends are hooked and engaged with staples 8 in the stringers. The upper end of the post is made cylindrical in form, thus leaving a shoulder 9, as seen in dotted lines, and this cylindrical portion is screw-threaded for a

short distance, for a purpose hereinafter stated.

C represents the pressing mechanism, which consists of a horizontal beam 10 and a screw 11, passed vertically through the beam. One end of this beam is journaled on the cylindrical portion of post B, being held in position thereon by the shoulder 9 and a nut 12 screwed on the threaded portion of the post. The outer end of the beam is held in proper position by means of tie-rods 13, whose lower ends are looped, as at 14, and passed over the projections 4 on the stringers, and whose upper ends are bent at an angle so as to embrace the sides of the beam, and are passed up through metal plates 15 and 16, on the lower and upper sides, respectively, of the beam, and are secured by nuts 17, as shown.

Midway longitudinally of beam 10 there is secured a perforated plate 18, screw-threaded interiorly, through which plate and a perforation in the beam registering with that in the plate is passed the pressure-screw 11, the upper headed end of which is perforated for the reception of a lever whereby to turn the screw, and to the lower end of the screw there is attached, preferably swiveled, a disk 19, affording an increased bearing-surface on the pressing-boards to be placed in the hogshead.

From what has already been stated, taken in connection with the drawings, the operation of my machine will be manifest without further description, as will also the expedition with which the work can be accomplished, the saving of the labor of moving a filled cask to position under the pressure-screw, and the facility with which the machine can be taken down and put up.

Having thus described my invention, what I claim as new, and desire to secure by Letters Patent, is—

1. In a tobacco-prizing machine, a platform capable of supporting two hogsheads or other casks and a post rising centrally from the platform of a beam journaled at one end on the upper end of the post, a pressure-screw passed through the central portion of said beam, and means for holding the outer end

of the beam in position, substantially as described.

2. In a tobacco-prizing machine, a platform capable of supporting two hogsheads or other 5 casks and having projections at each end and a post rising centrally from the platform of a beam journaled at one end on the upper end of the post, a pressure-screw passed through

the central portion of said beam, and tie-rods attached to the outer end of the beam and adapted to engage the projections on the platform, for the purposes stated.

JAMES H. CROW.
